UNITED STATES PATENT OFFICE.

ARTHUR LEON LEWIS, OF NEWTONVILLE, MASSACHUSETTS.

FILING DEVICE FOR BOUND CATALOGUES, BOOKS, &c.

1,275,054.

Specification of Letters Patent. Patented Aug. 6, 1918.

Application filed April 28, 1918. Serial No. 231,293.

To all whom it may concern:

Be it known that I, ARTHUR LEON LEWIS, a citizen of the United States, and resident of Newtonville, county of Middlesex, State of Massachusetts, have invented an Improvement in Filing Devices for Bound Catalogues, Books, &c., of which the following description, in connection with the accompanying drawing, is a specification, like 10 characters on the drawing representing like parts.

This invention relates to improvements in catalogues and the object thereof is to produce a bound or loose-leaf catalogue which 15 will be provided with identifying means whereby it may be easily filed in the proper section of a classified filing cabinet or suitably classified in some other repository.

At the present time, as in the past, catalogues are issued in the form of pamphlets, or books of various size, shape and thickness and when not in use are generally placed upon shelves in more or less miscellaneous order or put away in piles and 25 stacks and practically lost. Where catalogues of different size and thickness are thus stored upon shelves or in piles the thinner catalogues become lost for the reason that there is not sufficient area upon their 30 binding to receive identifying indicia. When, therefore, a thin catalogue is required it is usually necessary to pull out a large number of catalogues before the catalogue which is sought appears. In many 35 instances new catalogues are ordered to avoid the necessity of searching through miscellaneous files for the catalogue originally received. This unnecessary duplication of catalogues imposes a considerable 40 expense upon the concern issuing the publication.

The present invention is designed to provide a catalogue which can be made of a standard shape and size either to fit a standard filing cabinet or any other suitable filing 45 repository.

A further object of the invention is to provide a catalogue with means to receive identifying indicia by means of which a plurality of classifications may be applied so that the catalogue may conveniently be filed in different classifications.

A further object of the invention is to provide means whereby a catalogue or book

may be quickly located in its classified position, either by subject matter or from name without the necessity of referring to any index to ascertain its location as is a usual custom at the present time.

Certain preferred embodiments of my invention are illustrated in the drawings in which,

Figure 1 is a perspective view of a catalogue embodying my invention showing the book cover provided with a tab adapted to receive identifying indicia.

Fig. 2 is a similar view of the reverse side of the catalogue showing different indicia as applied to the tab.

Fig. 3 is a perspective view upon a small scale of the catalogue open at its middle to show the manner in which the leaves or signatures are fastened therein.

The book or catalogue illustrated in Figs. 1, 2 and 3 comprises a preferably rectangular cover having a front 1 and a back 2 which may be made of a single piece or may be of a plurality of members bound together along the rear edge 3 to contain a series of leaves or signatures 4. The leaves or signatures may be secured to and retained in the cover in any desirable manner known in the bookbinders' art. A convenient and common means which is illustrated herein comprises a plurality of staples 5 and 6 which pass through the folded line of the cover members 1 and 2 and through the folded edge of the leaves 4.

One of the covers, preferably the back cover 2 is provided with a tab 7 which projects upwardly preferably from the upper corner and may extend any suitable distance along the edge. This tab is adapted to receive indicating indicia 8, such for example as "Elevating trucks" illustrated, by which the catalogue may be readily identified. The tab 7 may receive on its reverse side other indicia 9 such as "L. S. Co.", so that the catalogue or book may be identified either by the subject matter or by the name of the concern issuing it or any other indicia which may be applied to it.

These catalogues preferably are made of a standard size corresponding to the cards or division cards of a usual standard filing system so that the catalogue may be readily placed in such a usual letter file without disturbing the system of classification used

2
therein. By thus providing a catalogue which can be readily filed the user of the catalogue will naturally place it in his letter file or cabinet where it will be readily accessible and easy to find when needed again.

By reason of this convenience the user will not be likely to destroy the catalogue or toss it into the miscellaneous pile where it will become lost; the expense therefore of duplication of catalogues by the firm issuing the same will be reduced very greatly and the delay and annoyance occasioned by searching for catalogues such as are now in use will be entirely eliminated.

15 It will be understood that the embodiments of the invention disclosed herein are illustrative merely and not restrictive and that various modifications may be made

within the meaning and scope of the following claim.

Having thus described my invention what I claim as new and desire to secure by Letters Patent is:

20 A catalogue in book form comprising a cover in which the leaves are permanently bound, a portion of one of the cover leaves projecting beyond the main edge and said portion having identifying indicia thereon so that when filed with other catalogues of substantially like size the projecting portion 25 permits of the ready selection of the desired catalogue.

30 In testimony whereof, I have signed my name to this specification.

ARTHUR LEON LEWIS.
